Fig. 4

FIG. 1 is a front elevational view of an ottoman, embodying my new design;

FIG. 2 is a side elevational view thereof;

FIG. 3 is a plan view thereof; and

FIG. 4 is an underside view of the same.

The appearance of the rear is like the front while the side not shown is a mirror image of the side shown.

This is a division of my pending application, Ser. No. D.13,532, filed on Sept. 13, 1968.

I claim:

The ornamental design for an ottoman, substantially as shown and described.
